UNITED STATES PATENT OFFICE.

ROBERT R. THOMPSON, OF BLOOMINGTON, ILLINOIS, ASSIGNOR TO THE NATIONAL MATTRESS MACHINE COMPANY, OF BOSTON, MASSACHUSETTS.

MATTRESS-STUFFING MACHINE.

SPECIFICATION forming part of Letters Patent No. 628,047, dated July 4, 1899.

Application filed June 11, 1898. Serial No. 683,181. (No model.)

To all whom it may concern:

Be it known that I, ROBERT R. THOMPSON, a citizen of the United States of America, residing at Bloomington, in the county of McLean and State of Illinois, have invented certain new and useful Improvements in Mattress-Stuffing Machines, of which the following is a specification.

My invention relates to certain new and useful improvements in mattress-stuffing machines, the object being to produce a simple, practicable, and comparatively inexpensive machine for stuffing mattresses. Especial attention has been given to the construction of the adjustable box for containing the material to be compressed, the compression top or cover, and certain other auxiliary operating mechanisms which complete the machine, a description of which will be found in the following specification and the essential features definitely pointed out in the claims appended thereto.

The invention is illustrated in the accompanying drawings by means of ten figures, of which—

Figure 1 is a side elevation of a complete machine. Fig. 2 is a vertical central longitudinal section thereof, the section being taken in line 2 2 of Fig. 6. Fig. 3 is a vertical cross-section in line 3 3 of Fig. 1. Fig. 4 is a perspective view of the forward end of the machine, certain portions being broken away to expose other important parts. Fig. 5 is a detail perspective view of one of the corner-posts and compression-rods. Fig. 6 is a view partly in top plan and partly in horizontal section, the line of section being taken at 6 6 in Fig. 1 and certain portions broken away to expose more important parts. Fig. 7 is an enlarged detail vertical section of a clamp for fastening the side rails to the floor, the line of section being taken at line 7 7 in Figs. 6 and 8. Fig. 8 is a plan view of said clamping device, the side rail being shown in horizontal section and the line of section being taken at line 8 8 in Fig. 7. Fig. 9 is an enlarged detail cross-section of one of the side rails, the line of section being taken at 9 9 in Fig. 6; and Fig. 10 is an enlarged detail perspective view of a portion of the forward end

of the machine, including the side rail, gate, and appurtenances.

In the views, A A A A represent the four corner-posts of the machine, and a a' a² certain longitudinal and transverse connecting members adapted to make a preferably rigid framework. Upon the transverse members a² is secured a platform or floor A', having along its center a longitudinal slot a⁴, in which slides the neck b of a plunger B, which is adapted to force the compressed material out through the open end of the box and into the tick or mattress-covering.

Upon the platform or floor are adjustably secured two side rails C, forming the sides of the box into which the material is placed. They are vertically expansible in order that when the loose material is placed in the box the side rails may be of sufficient height to contain the quantity of material necessary to fill a mattress. As seen in Figs. 2, 3, and 9, a hood C', U-shaped in cross-section, embraces the board C and is supported above the same by springs c c', the spring c being secured in a notch in the upper face of the board C and having one end impinging upon the upper portion of the hood and the spring c' being secured to one end of a rod c², which passes through an opening in the board C and is secured to the top of the hood C', as seen in Fig. 9. The other end of the spring c' is secured in a suitable screw-eye or staple c³, fastened to the board C. The tension of both springs is sufficient to raise the hood to the position shown in the drawings whenever downward pressure upon the same is removed. The hoods are preferably formed of thin sheet metal, and to prevent bending or accidental displacement of the same with reference to the board C a stiff bar C² (see Figs. 1 and 2) is pivoted to the hood at c⁴ and extends obliquely downward and rearward into a recess provided therefor in the board C. This end of the bar is slidingly secured to the board C by a headed pin c⁵, running in a slot c⁶ in the bar, which allows the vertical movement of the hood with reference to the board C.

The side rails are adapted to be adjusted laterally in order to form different widths of

mattresses and for the purpose of rigidly securing them to the platform or floor clamps D are provided. The clamps are secured to the side rails, as seen in Figs. 1, 6, 7, and 8, 5 and are formed with bosses d, having the inclined upper faces d'. (See Fig. 1.) In these bosses are pivotally secured cranks d², having pivot portions d³ passing through the bosses and hooks d⁴, formed upon the ends of 10 the pivot portions. A series of holes d⁵ are made in the floor, as seen in Fig. 6, and upon the under side thereof are secured perforated bars D', upon which the engaging ends or hooks d⁴ impinge when the clamps are in a 15 locked position. In the drawings the clamps are shown in such a position, and in Fig. 7 the crank is shown in dotted lines as swung into a diametrically opposite position and raised above the platform, the engaging portion 20 d⁴ entering a socket d⁶, formed in the boss d. When the cranks d² are in the position shown in dotted lines in Fig. 7, the side rails may evidently be adjusted laterally to the position desired, and when such position 25 is attained the levers may be dropped through the adjacent openings d⁵ and swung into the position shown in full lines, the movement of the crank upon the inclined face d' of the boss raising the engaging end d⁴ and crowding 30 it against the perforated bar D', thereby rigidly clamping the side rails to the platform or floor.

Upon the forward ends of the side rails is secured a spout adapted to move with the 35 side rails and upon which the tick is slipped when the stuffing material has been compressed and is ready to be forced into the tick. As shown, the spout consists of two U-shaped sheet-metal portions E E', the ends of 40 the portion E preferably overlapping the ends of the portion E', so that when the spout is in its expanded position a perfect rectangular tube will be formed. Looking at Fig. 10, two brackets e e' are secured to the side bar 45 C, the bracket e being secured to the upper portions of the two halves E E', which form the spout, and the bracket e' extending below the bottom of the side board C, where it is bent back upon itself in a U shape e² (see 50 Fig. 10) and then outwardly in a plane at right angles to the main portion and secured to the under sides of said halves E E' of the spout, as seen in Fig. 4. As shown in Figs. 2 and 4, the upper and lower sides of the 55 spout adjacent to the head-board a³ and transverse bar a² of the machine are bent at right angles and back upon themselves and slide in brackets e⁴ e⁵, the object being to prevent these portions from buckling inward and obstructing the passage-way.

Between the ends of the side rails and the spout is pivoted a gate F, adapted to close up the end of the box when desired and to be swung down into a horizontal plane, so 60 as to allow the stuffing material to pass over the same. As shown, the lower edge of the gate is wrapped around a rod f, which is

journaled upon the posts A (see Fig. 4) and is bent at right angles upon its ends to form handles f⁵, by means of which the end gate 70 may be oscillated. The end portions of the spout are cut away, as seen at e⁶, to permit the gate to be swung downward without striking the spout, and the edges thus formed by cutting away the arc are preferably bent outward in order that the stuffing material may pass rapidly into the spout and not engage upon these edges. At a convenient place above the gate is journaled a rod f', having upon its ends suitable handles f² for operating the same. A pair of dogs f³ f³ (see Figs. 4 and 9) are secured upon the rod f' at points near the ends of the gate F, these dogs being adapted to engage the gate and prevent the same from being swung down when compressing the material within the box. Pins f⁴ are provided upon the posts A, limiting the movement of the handles in one direction, and when the same are swung in the direction indicated by the arrow in Figs. 1, 4, and 10 90 the dogs are swung upward out of engagement with the gate, thereby allowing the same to be swung downward, so that the compressed material may be forced out through the opening in the end of the box. 95

The compression top or cover G is seen in Figs. 1 to 4, inclusive, and is provided with suitable longitudinally and transversely extending trusses g g', adapted to give the necessary stiffness to the same. When in the position shown in the drawings, the cover is supported by four compression-rods H H H' H', pivoted at their lower ends to levers i i', mounted upon transversely-extending shafts I I', journaled upon the posts A of the frame. (See 105 Figs. 2 and 3.) The upper ends of the compression-rods are notched, all of the notches opening toward the front of the machine, and in these notches rest gudgeons g², which are secured to the cover G at or near the corners. 110 It should be noticed that the notches of the compression-rods H are slightly higher than the other notches, the rear gudgeons g² being correspondingly higher than the gudgeons upon the forward end of the frame, the object 115 being to permit the rear gudgeons to pass over the tops of the compression-rods H' without striking them when the cover is removed from the position shown in the drawings—that is, when the box is uncovered for the purpose of 120 filling it with the material to be compressed. It is obvious that when the cover rests upon the compression-rods H H' the latter are held thereby in an approximately upright position; but when the cover is removed from the compression-rods it is necessary to provide means 125 for supporting them until again connected to the cover. Looking at Figs. 1 and 5, a plate S will be seen secured to the inner faces of the posts A, said plate being formed with a notch s, lying in the path of a pin s' upon the compression-rod. When the rod is in its highest position, the pin s' rests in the notch and holds the rod in an upright position and at the 130

same time in the proper position so that the gudgeons will enter the notches h h' when the cover is brought into position upon the box.

The shafts I I' are provided upon their outer ends with sockets i^2 , into which are inserted levers I^2 , (see Fig. 1,) by which the cover is raised or lowered. In order that the cover may be evenly raised or lowered at the four corners, it is necessary that the shafts I I' rotate in unison, and for this reason they are connected by suitable means which cause them to travel together. The means here shown consists of two sprocket-wheels i^3 i^4 , mounted upon the shafts I I' and connected by chains i^5 i^6 of suitable length to sufficiently rotate the sprocket-wheels, and their ends connected by rods i^7 , each rod extending from the upper end of one chain to the lower end of the other, thereby reversing the direction of movement of the sprocket-wheels and at the same time causing them to move in unison.

When the machine is to be loaded with the stuffing material, the cover is slid away from its position shown in the drawings by the operator. Looking at Figs. 1, 2, and 6, two legs g^8 will be seen secured to the rear corners of the cover, and in the lower ends of the legs are journaled flanged rollers g^4 , adapted to run upon the longitudinal edges of the platform. When the cover is in the position shown, the rollers do not rest upon the platform, but are suspended beyond the rear end thereof, the platform extending merely to the rear face of the posts A. (See Fig. 6.)

Along the middle line of the cover and upon the under side thereof is formed a longitudinal groove g^5 , (see Figs. 2 and 3,) adapted to embrace the web j of a T-iron J, one end of which is supported by the head-board a^3 and the other end by a standard or frame j' . As the cover rides out upon the T-iron the groove therein prevents the cover from any lateral movement. At various points in this groove are journaled rollers j^6 to avoid the friction between the T-iron and cover as the latter moves thereon.

The positions of the rollers g^4 with respect to the rear edge of the platform A' and of the forward roller g^6 with respect to the end of the T-iron J are such that the rollers will engage and rest upon the platform and T-iron, respectively, at or before the instant the gudgeons g^3 leave the notches in the compression-rods H H', thereby insuring a perfectly even motion of the cover in sliding it on or off the T-iron. The forward edge of the cover is so arranged with respect to the head-board a^3 that when it is lowered it will not strike the latter, the rollers g^4 also passing by the rear edge of the platform.

The plunger B, above referred to, is made laterally expandable by means of two boards b' b' , held in front of the plunger-head by a hook b^2 . (See Figs. 2 and 6.) A rack-bar B' is located below the platform A' and is connected to the plunger by the neck b, running in the groove a^4 . The other end of the rack-

bar is supported by and in mesh with a pinion p , loosely mounted upon a shaft P, (see Figs. 1, 2, 3, and 6,) journaled in suitable bearings mounted upon the frame of the machine. A clutch p' connects the pinion with the shaft, and said clutch is operated by a lever p^2 , having a portion lying in the path of the neck b, so that as the latter strikes the lever p^2 it throws the clutch out of engagement with the pinion, thereby preventing the plunger from being forced ahead too far.

The shaft P is rotated by suitable gearing interposed between it and a crank r, (see Fig. 1,) secured upon the end of a shaft R, said gearing comprising a pinion r' , fast upon the shaft R, meshing with a gear r^2 upon the shaft P. By rotating the crank r in the proper direction power is transmitted to the plunger B and the latter forced forward, crowding the compressed stuffing material out through the spout.

In operating this machine the cover is first slid upon the T-iron, thereby exposing the box, which is filled with stuffing material sufficient for the desired mattress. The cover is then pushed back until the gudgeons rest in the notches h h' and the rollers g^4 g^6 are free from the platform and T-iron, respectively. The levers I^2 are then swung toward each other until the cranks i i' are carried by the dead-centers, thereby bringing the cover down upon the mattress material and compressing it, the hood C' being pushed down upon the side board C by the cover. The gate being in its raised position, the crank r is rotated in the proper direction, thereby crowding the compressed material against the end gate F in order to compress it longitudinally. The tick is then placed on the spout, the gate swung down, and the plunger carried forward by the further rotation of the crank r until the stuffing material has been entirely ejected from the spout. The plunger is then pushed backward to the position shown in the drawings, the end gate raised, the cover slid away from the box, and the machine is in position to be reloaded.

I am aware that various alterations and modifications of the different portions of the machine are possible, and I desire, therefore, not to limit myself to the exact construction shown and described.

I claim as new and desire to secure by Letters Patent—

1. In a machine of the class described, a press-box having a suitable top and bottom, one of which is movable toward and from the other, and side rails one of which is vertically expandable and compressible and laterally adjustable with respect to the box; substantially as described.

2. In a mattress-stuffing machine, a press-box having a vertically expandable and compressible side rail; substantially as described.

3. In a machine of the class described, the combination of a rigid framework, a bottom fixed thereto, a vertically-movable top and

suitable side rails, one of which is vertically expandible and compressible and laterally adjustable between said top and bottom; substantially as described.

5 4. In a machine of the class described a side rail embraced between the top and bottom and made up of a rigid portion and a portion vertically movable with respect thereto and provided with a spring tending to keep it in its 10 vertically-extended position; substantially as described.

5. In a machine of the class described, a press-box having a vertically and horizontally movable cover, means for moving said cover 15 vertically to press the stuffing material and means for sustaining said cover adapted to permit it to be moved horizontally to uncover the press-box when the stuffing material is to be placed therein; substantially as described.

20 6. In a machine of the class described, a press-box having a vertically and horizontally movable cover, means for moving said cover vertically to compress the stuffing material said means containing devices engaging said 25 cover against vertical, but not against horizontal movement in the direction desired and means for sustaining said cover when moved in the proper direction to uncover the box; substantially as described.

30 7. In a device of the class described, a laterally-adjustable side rail having an extension forming part of a spout, and a pivoted or hinged gate pivoted at any side between the side rail and the spout, said extension being 35 cut away to allow the gate to swing upon its hinge, from a vertical position adjacent to the end of the side rail to a horizontal position within the spout; substantially as described.

8. In a machine of the class described, a press-box having a suitable bottom and top 40 and containing a compressible side rail formed with two overlapping portions provided with springs tending to extend the side rail to its greatest width; substantially as described.

9. In a machine of the class described, a 45 press-box having in combination with suitable top and bottom a vertically compressible and expandible side rail composed of the relatively stationary portion, C, and the U-shaped movable portion, C', overlapping the portion, 50 C, upon both sides and forming a hood therefor and means for extending said side rail; substantially as described.

10. In a machine of the class described, the combination with a suitable press-box and a 55 horizontally and vertically movable cover provided with means of engagement therewith, of the hooked arms, H, adapted to engage with said cover to prevent movement thereof, except in a horizontal direction, said arms being pivoted at their lower ends to oscillating cranks connected together and provided with means for their oscillation and devices for engaging the upper portions of said arms against horizontal movement at the upward 60 limit of their movement; substantially as described.

In witness whereof I have hereunto set my hand, at Bloomington, in the county of McLean and State of Illinois, this 4th day of 70 June, A. D. 1898.

ROBERT R. THOMPSON.
